LASTING MACHINE

Philipp Vollhardt, Oberursel, Taunus, Germany, assignor to Eugen G. Henkel, Maschinenfabrik, Neu-Isenburg, Germany, a firm of Germany

Filed May 25, 1962, Ser. No. 197,794

Claims priority, application Germany, Jan. 4, 1962, H 44,530; Jan. 9, 1962, H 44,562
21 Claims. (Cl. 12—12)

The present invention relates to a lasting machine, and more particularly to a shank lasting machine.

The conventional lasting machines for lasting the toe and heel parts of shoes generally operate with so-called wipers which are pivotable like shears about a fulcrum which is located in front of the toe or heel portion of the last and within a plane which extends parallel to the bottom of the respective portion of the last. When these wipers are moved in the direction toward the last, the jaws thereof press the lasting margin of the upper against the insole on the bottom of the last so that the lasting margin may at the same time be cemented to the insole.

The operation of lasting a shoe by means of such wipers involves no particular difficulties as long as the bottom of the last lies within the same plane as the flat operating side of the jaws. The lasting operation of the conventional lasting machines is therefore generally limited to the area between the toe or heel portion of the last and the beginning of the shank which corresponds to the instep of the foot. The shank area can therefore not be reached by the mechanical lasting operation since the bottom of the last deviates within this area from the plane of the operating side of the flat wiper jaws.

In order to permit the lasting work to be carried out mechanically also within the shank area, the wipers of one prior lasting machine have been subdivided within this area into a plurality of fingerlike elements which are pivotable independently of each other relative to the bottom of the last and are adapted to press under spring action or under their own elasticity against the shank area of the last bottom. When the fingerlike elements are moved toward the last bottom, they first carry out a pivoting movement about their axis and then assume a position which more or less corresponds to the shape of the shank.

The last-mentioned shank lasting machine has, however, the disadvantage that the operating side of the fingerlike elements only engages with a very small part of the lasting margin of the upper so that usually there is hardly any more than a pointlike engagement, while toward the edge of the lasting margin the fingers usually no longer engage at all. Consequently, in this type of lasting machine the lasting margin of the upper is pressed against the insole with a rather low pressure or the pressure is limited to a few small points. The effect of this deficiency is especially serious in cement lasting where it is very important that the lasting margin of the upper is cemented uniformly at all points to the insole. This can be attained, however, only if the machine is designed so that the wipers press the lasting margin along its entire width and also within the shank area against the insole. This, however, is impossible with the mentioned shank lasting machine.

The present invention as subsequently described is based upon the recognition of the important fact that the mentioned deficiency of the known shank lasting machine as above referred to is due to the fact that the fingerlike wiper elements themselves are pivotable about a horizontal axis.

There is another known shank lasting machine in which the individual fingerlike shank wipers are adjusted to the

shape of the shank and the height of the heel portion of the particular last not by carrying out a pivoting movement about a horizontal axis but by being slidable within a vertical plane to different positions parallel to each other. The ends of the fingers opposite to the operating ends are for this purpose mounted in a curved guide, the pitch of which is adjustable. In this manner it is possible to adjust the shape of the curve which is formed by a connection between the operating ends of the fingers so as to comply to some extent with the inclination of the shank. A perfect adjustment of the operating curve to the shape of the shank is, however, not possible because the fingers are movable within a common guide and are therefore not adjustable relative to the last bottom completely independently of each other. This machine can therefore not be used for working on more or less unusual types of lasts. This disadvantage can also not be avoided by making the fingers of an elastic construction since such an elasticity would prevent the fingers from being applied upon the lasting margin with the high contact pressure which is essential in order to attain a proper cementing of the lasting margin to the insole.

A further disadvantage of the last-mentioned shank lasting machine is the fact that the curve which is formed by a connection between the operating ends of the fingers only extends within a single vertical plane and not also within the horizontal plane. This machine therefore does not take into account the fact that within the area of the shank and especially at the inner side thereof, the contour of the last is curved inwardly, that is, toward its center. If, as in this known shank lasting machine, all of the operating ends of the fingerlike shank wipers lie only within a single vertical plane, the effective side or edge of the operating end of each finger which is, for example, of a beveled shape will not engage along its entire length with the lasting margin, but will partly project over the margin. Naturally, this is very detrimental especially in cement lasting.

The known shank lasting machines also do not take into account the fact that the extent of the shank increases with the increase in the size of the shoe so that a fixed number of wiper fingers as provided in these known machines will not always be sufficient for lasting the same anatomical area of lasts of different sizes.

It is an object of the present invention to provide a shank lasting machine which overcomes the aforementioned disadvantages and is generally of the type as previously described which is provided with shank wipers which are subdivided into a plurality of fingerlike elements which are individually movable relative to the bottom of the last to different positions parallel to each other.

The basic concept of the invention for attaining this object is to provide suitable means to permit the fingers by being movable independently of each other to move from a basic position in which they are spaced from the bottom of the last automatically to their operative position in which they are in engagement with the bottom of the last. This, in turn, permits the operating end of each finger to be adjusted in a very simple manner relative to the bottom of the last independently of the adjustment of the operating ends of the other fingers. The fingerlike wipers will thus adapt themselves very quickly, without any manual operation, and very accurately to the size and contour of any shank which was previously impossible when the rear ends of the fingers were mounted in a common guide.

The structural embodiment of this principal concept of the invention may consist in pivotably mounting the rear ends of the fingers on one or more levers which, in turn, are capable of swiveling about one or more axes

relative to the bottom of the last. Each finger is preferably associated with two of these levers which are disposed above and spaced from each other and are mounted on two pivots which are likewise disposed above each other. According to a preferred embodiment of the invention, the desired movability of the fingers may be attained by providing the rear end of each finger with a crosspiece so as to be of a T-shaped construction, by making the two ends of this crosspiece of a spherical or cylindrical shape, and by rotatably mounting these two ends in bearings of a corresponding shape on the ends of the two levers.

By this double pivotable suspension of each finger on a pair of levers which are mounted on separate pivots it is possible in a very simple manner to guide the fingers so that during their adjustment relative to the bottom of the last they will always extend parallel to each other.

In order to insure that the lasting margin of the upper will be strongly pressed by the fingerlike wipers against the insole, these fingers are not made in the conventional manner of an elastic construction but of a rigid construction. According to one preferred embodiment of the invention the pressure of the fingers against the bottom of the last is produced by means of springs.

The shank lasting mechanism according to the invention is preferably applied to a combined pulling-over and lasting machine. The movement of the entire pack of fingers may then be carried out automatically in a manner known as such in response to the operation of the pulling-over grippers.

The objects, features, and advantages of the present invention will become more clearly apparent from the following detailed description thereof which is to be read with reference to the accompanying drawings, in which—

FIGURE 1 shows a side view of the shank lasting apparatus according to the invention;

FIGURE 2 shows a plan view as seen in the direction of the arrow II in FIGURE 1;

FIGURE 3 shows a view of the lasting apparatus as seen in the direction of the arrow III in FIGURE 1, and also indicates the alternate arrangement of two different lasts relative to the mechanism;

FIGURE 4 shows a view similar to FIGURE 3, but in which the levers are omitted;

FIGURE 5 shows a plan view similar to FIGURE 2 of a lasting mechanism according to a modification of the invention;

FIGURE 6 shows a view similar to FIGURE 3 of the modified apparatus according to FIGURE 5;

FIGURE 7 shows a perspective view of a toe or heel wiper together with the associated auxiliary wiper fingers;

FIGURE 8 shows the mounting of one of the auxiliary fingers with slightly different fingers being used.

The mechanism for lasting the shank of a shoe which in the illustrations of the first embodiment of the invention, that is, in FIGURES 1 to 4, is generally indicated at 1 is connected to the frame of the lasting machine by means of arms 2, the front ends of which carry bushings 3 on which by means of pins 4 a supporting plate 5 is mounted. On this supporting plate 5 the actual shank lasting mechanism 1 is slidably mounted by means of guide members 6. As shown particularly in FIGURES 3 and 4, for sliding the lasting mechanism 1 along the supporting plate 5 a handwheel 7 is provided which is connected to an adjusting spindle 8 which is rotatable within a bearing plate 9 which is secured to the lasting mechanism by screws 10, while a flange 11 prevents spindle 8 from moving in the axial direction. The front end of spindle 8 engages into a threaded bore in a projection 12 on the supporting plate 5.

The lasting mechanism 1 is mounted within a cage-like housing consisting of the two parts 13 and 14 which are secured to each other by screws 15. Within housing 13, 14 a plurality of wiper fingers 16 are mounted in a man-

ner as subsequently described. The front ends of these fingers 16 are provided with beveled surfaces 17 which form the operating surface of the fingers and are adapted to press the lasting margin of the upper with the necessary pressure against the insole so as to attain a good and secure cementing effect. A similar lasting mechanism 1 is provided on each side of the last within the area of the shank of the shoe.

As illustrated in FIGURE 1, each finger 16 is substantially T-shaped by being provided on its rear end which extends into housing 13, 14 with a crosspiece 18. The ends 19 of this crosspiece 18 are circularly rounded and engage into corresponding circular recesses 20 which are provided in the front ends of a pair of suspension levers 21 which are mounted at their rear ends on a pair of shafts 22. Each finger 16 is therefore mounted on a separate pair of suspension levers 21 and may thus be moved independently of the other fingers 16. Levers 21 are pivotable about shafts 22 and also about the circular ends 19 of the crosspieces 18. The distances between the centers of both shafts 22 and the centers of the circular ends 19 of each crosspiece 18 is equal. Since both levers 21 on each crosspiece are also of the same size, they form a parallelogram as the result of which the positions to which fingers 16 may be moved will at any elevation extend parallel to each other.

At the beginning it has been pointed out that it is one disadvantage of the known shank lasting machines that the curve which is formed by a connection between the operating ends of the fingers only extends within a single plane. Therefore, the fingerlike members cannot adapt themselves sufficiently to the contour of the shank. In order to overcome this disadvantage, the present invention provides that the operating ends of the fingers are adjustable along a tridimensional curve. When all of the fingers 16 are of the same length as illustrated in FIGURE 2, this may be attained by making the shafts 22 not of a straight shape but by curving them in the direction toward the tips of the fingers 16 so that the curvature corresponds at least substantially to the shape of the shank area of the last at the side facing the shafts. Therefore, although all of the fingers 16 are of the same length, they project for different distances from the housing 13, 14. Since all of the fingers are of the same length, the connecting line 23 between the finger tips, that is, the operating curve, corresponds exactly to the curvature of shaft 22 when all fingers 16 are disposed at the same level, that is, when they are in the neutral position. In the operating position, however, fingers 16 are disposed at different levels since they must adapt themselves to the arched contour of the shank. The curvature of shafts 22 may be designed so that the connecting line 23 between the finger tip 17 corresponds to the contour of the shank of a medium-sized last.

For adapting the lasting mechanism 1 to shoes of different sizes and shapes and thus to different shanks, it is provided with an adjustment device which permits the shafts 22 to be shifted in the axial direction. For this purpose, the ends 24 of shafts 22 are mounted in slide members 25 and 26 which are secured by nuts 27 by means of which the slide members may be tightened against the shoulders 28 of shafts 22. Slide member 25 is slideable within an aperture 29 in the housing part 13, while slide member 26 is slideable within a corresponding aperture 30 in the housing part 14. Aperture 30 is closed by a cover 31 which is secured to housing part 14 by screws 32. In cover 31 an adjusting spindle 33 is rotatably mounted which is prevented by a flange 34 from shifting in the axial direction and carries on its outer end a control knob 35. The threaded front part of spindle 33 is screwed into a threaded bore in slide member 26. Since spindle 33 is fixed in the axial direction, slide member 26 will be shifted within aperture 30 when control knob 35 is turned, and both shafts 22 together with the other slide member 25 will then also be shifted

in the axial direction. By this movement, the two sets of levers 21 which are mounted closely adjacent to each other on shafts 22 are shifted along the shafts and thereby move to another area of the curvature of the shafts. This, in turn, changes the shape of the operating curve 23 which may in this manner be adapted to the different shapes and contours of the shanks or lasts of shoes of different shapes and sizes.

Each set consisting of a finger 16 and a pair of levers 21 is acted upon by a spring. In the particular embodiment of the invention as illustrated in FIGURES 1 to 4, torsion springs 36 together defining a spring assembly are provided for this purpose. One arm 39 of each of these springs acts upon the lower side of the lower lever 21 and the other arm 38 acts upon another element of mechanism 1. Spring 36 tends to press the lower lever 21 and thus also the upper lever 21 and the finger in the upward direction.

In order to arrest all fingers 16 at a certain elevation, a locking device is provided which consists of a clamping fixture which may be operated by a handle 40. Hub 41 of handle 40 is secured by a pin 42 to an eccentric shaft 43 which is mounted in an upper bore 44 and a lower bore 45 which are provided in corresponding projections on the housing part 14. The central part 46 of shaft 43 forms an eccentric which engages upon the outermost levers 21. When handle 40 is turned to a certain extent, the eccentric 46 will be turned so that the intermediate member 47 presses the entire pack of levers and fingers against the side wall of the housing part 13. The eccentric 46 is made of such an eccentricity and handle 40 is made of such a length that only a relatively small force needs to be applied on the handle in order to exert such a strong clamping effect that the fingers 16 may be locked securely at any level and will then not yield under the operating pressure with which they are pressed against the last.

In order to move all of the fingers 16 to a basic position and to lock them therein when the machine is in the inoperative position, a further locking device is provided which, as illustrated in FIGURES 1 and 2, is operated by a handle 48 which is secured to a lever 50. This lever 50 is pivotable about a shaft 49 which extends across the entire width of housing 13, 14 and around which the actual locking lever 51 is pivotable. This locking lever 51 is secured to the adjusting lever 50 by bolts 52. When the mechanism is in the position as illustrated in FIGURE 1, all fingers 16 are pressed downwardly and the lower rounded end of locking lever 51 engages upon the upper side of fingers 16.

For adjusting the shank lasting mechanism 1 to a last of a particular shape (two different lasts 53 and 54 being indicated in FIGURE 3), the following procedure is followed:

First, by pivoting the second locking device by means of the handle 48, all fingers 16 are pressed downwardly and are at first left in this position in which they are all spaced from the bottom of the subsequently inserted last. After the last 53 or 54 is inserted, locking lever 51 is pivoted upwardly toward the right, whereupon fingers 16 will move upwardly under the action of springs 36 until the beveled ends 17 of the fingers engage upon the lasting margin of the upper. After the fingers have thus adapted themselves automatically to the shape of the last and have thereby formed a curve in accordance with the shape of the shank of the respective last, the clamping lever 40 is turned, whereby all fingers 16 are arrested in the adjusted position and form a rigid unit. This completes the adjustment of the shank lasting mechanism so that the production can then be started.

In the actual lasting operation, the entire mechanism is moved by an appropriate movement of the supporting arms 2 in the direction toward the last so that the beveled operating surfaces 17 of the fingers draw the upper firmly over the edge of the last and press it upon the insole.

The modification of the invention as illustrated in FIGURES 5 and 6, differs from the embodiment as previously described by the fact that in place of the curved shafts 22 on which the fingers are mounted in FIGURES 1 to 4, shafts 56 in FIGURES 5 and 6 are straight, and that the tridimensional connecting line 57 between the tips of fingers 55 in accordance with the particular contour of the last is attained by making the fingers 55 of different lengths.

Furthermore, the apparatus according to FIGURES 5 and 6 is equipped with an auxiliary device which, however, may also be applied to the apparatus according to FIGURES 1 to 4, and which is provided for permitting a lasting operation to be carried out within the same anatomical area on larger lasts as on smaller lasts. This is of importance inasmuch as an increase in the size of the last also results in an increase in the size of the shank. The set of fingers as illustrated in FIGURE 2 therefore does not permit the lasting margin to be worked upon within the entire area of the shank of larger lasts. This will be clearly apparent from FIGURE 3 which indicates the range of operation of the finger pack on a large last and on a small last. The invention therefore provides between the toe or heel wipers and the finger pack an auxiliary device in the form of auxiliary wiper fingers 58 or 58', as illustrated in FIGURES 7 and 8, respectively, and which are adapted to extend the range of operation of the shank lasting mechanism. The fingers 58' shown in FIGURE 8 are slightly different from those shown in FIGURE 7. Depending upon the position of the shank lasting mechanism which may be shifted in the same manner as in the first embodiment by means of a control knob 59, as shown in FIGURE 6, a larger or smaller number of auxiliary fingers 58 or 58' will be made effective between the ends of the wiper plates 60 and 61 and the finger pack 55 of the shank lasting mechanism. The unused fingers 58 or 58' then engage upon stop edges 62 and 63 of jaws 60 and 61.

For automatically moving the auxiliary fingers 58 forwardly, they are mounted in the manner as shown in FIGURE 8 so as to be slidable in the longitudinal direction, that is, parallel to the operative side of the wiper plates 60, 61. The plane of action of the auxiliary fingers 58 or 58' lies within the extension of the plane of action of plates 60, 61. Fingers 58 or 58' are provided with elongated slots 64 in which a pin 65 engages. The movement of each finger 58 or 58' is effected by a separate compression spring 66, one end of which acts upon the respective finger and the other end upon the housing. The operating position of the fingers is reached when the rear end of slot 64 engages upon pin 65, provided that the tips of the auxiliary fingers 58 or 58' have not previously come to rest upon the stop edges 62 and 63.

In order to permit the auxiliary fingers to be moved automatically to their operating position when the cage 13, 14 for the finger pack 16, 55 is adjusted, for example, in a toe lasting machine, more toward the heel of a larger last, the housing or supporting frame for the auxiliary fingers is connected to cage 13, 14 (see FIGURES 6 and 8). The distance at which the cage 13, 14 is adjusted from the ends of the wiper plates therefore determines the number of auxiliary fingers which are retracted from the stop edge 62, 63 and are moved into their operative position.

In order to prevent the auxiliary fingers in the operating position from being pushed back when being moved against the last which might prevent a proper cementing, a stop member 67 is provided at the rear end of the auxiliary fingers 58 or 58', as illustrated in FIGURES 7 and 8. This stop member which is stationary and secured, for example, to the supporting plate 5 locks the forwardly moved auxiliary fingers in their operating position. As illustrated in FIGURE 7, fingers 58 or 58' are placed in front of the stop member 67 to the extent at which they are drawn away from the stop edge 62

and 63 of the plates 60 and 61 during the movement of the cage away from the plates.

Of course, when smaller lasts are being used, the auxiliary fingers remain inoperative, while when a last of the largest size is applied, all auxiliary fingers will be in operation.

The toe or heel wipers 60, 61 according to FIGURE 7 which are conventionally provided in the form of tongs and are employed for lasting the toe or heel are preferably provided with extensions 68 and 69 which project beyond their effective area within which they press the lasting margin from the tip of the toe or from the end of the heel up to the beginning of the shank against the insole. These extensions 68 and 69 preferably extend along the area of operation of the auxiliary fingers 58 so that the folds of the lasting margin which are formed within the area of the beginning of the shank and are out of reach of the plates 60 and 61 themselves when they are pivoted toward each other, will then be folded by the extensions against the insole in the direction toward the shank. In prior lasting machines, these folds always projected from the insole and thereby interfered with the inward movement of the shank wiper fingers. These extensions of the jaws give the folds a positive support so that the folds will then be placed in a position in which the inwardly moving fingers 58 can easily move underneath them and press them effectively against the insole, thus insuring that these folds will be properly cemented to the insole.

As may be clearly seen in FIGURE 7, fingers 58 are movable into the gap between the insole, not shown, and the upper side of the jaw extensions 68 and 69 facing the insole. In order to make this gap of the proper width to accommodate the fingers 58 it is advisable to offset the extensions 68, 69 sufficiently relative to the upper side of plates 60, 61.

Although my invention has been illustrated and described with reference to the preferred embodiments thereof, I wish to have it understood that it is in no way limited to the details of such embodiments, but is capable of numerous modifications within the scope of the appended claims.

Having thus fully disclosed by invention, what I claim is:

1. In a lasting machine, a shank lasting mechanism comprising a plurality of individual wiper fingers at least at one side of a central vertical longitudinal plane of a last, means for mounting each of said fingers so as to be movable within a vertical plane into one of a plurality of positions which are parallel to each other and independently of the other fingers from a basic position spaced from the bottom of the last to an operative position in engagement with the bottom of the last, and resilient means acting upon each of said fingers for moving said finger toward said bottom.

2. In a lasting machine, a shank lasting mechanism comprising a plurality of individual substantially non-resilient wiper fingers at least at one side of a central vertical longitudinal plane of a last, means for mounting each of said fingers so as to be movable within a vertical plane into one of a plurality of positions which are parallel to each other and independently of the other fingers from a basic position spaced from the bottom of the last to an operative position in engagement with the bottom of the last, and at least one spring acting upon each of said fingers for moving said finger toward said bottom.

3. In a lasting machine, a shank lasting mechanism comprising a plurality of individual wiper fingers at least at one side of a central vertical longitudinal plane of a last, means for mounting each of said fingers so as to be movable within a vertical plane into one of a plurality of positions which are parallel to each other and independently of the other fingers from a basic position spaced from the bottom of the last to an operative position in engagement with the bottom of the last, resilient means acting upon each of said fingers for moving said finger

toward said bottom, and means for locking said fingers in said basic position against the action of said resilient means.

4. In a lasting machine, a shank lasting mechanism comprising a plurality of individual wiper fingers at least at one side of a central vertical longitudinal plane of a last, and means for moving each of said fingers within a vertical plane into one of a plurality of positions which are parallel to each other and independently of the other fingers from a basic position spaced from the bottom of the last to an operating position in which the front ends of said fingers are in engagement with the bottom of the last, said means comprising a plurality of levers, means pivotally connecting each of said fingers at its rear end to the front end of at least one of said levers, and means for pivotally mounting said levers at their rear ends.

5. In a lasting machine, a shank lasting mechanism comprising a plurality of individual wiper fingers at least at one side of a central vertical longitudinal plane of a last, and means for simultaneously moving each of said fingers within a vertical plane into one of a plurality of positions which are parallel to each other and independently of the other fingers from a basic position spaced from the bottom of the last to an operating position in which the front ends of said fingers are in engagement with the bottom of the last, said means comprising a plurality of levers arranged in pairs, means mounting the two levers of each pair spaced from each other, means for pivotally connecting the rear end of each of said fingers to the front ends of said two levers, and means above and spaced from each other for pivotally mounting said two levers for each finger at their rear ends.

6. In a lasting machine, a shank lasting mechanism comprising a plurality of individual wiper fingers at least at one side of a central vertical longitudinal plane of a last, and means for moving each of said fingers within a vertical plane into one of a plurality of positions which are parallel to each other and independently of the other fingers from a basic position spaced from the bottom of the last to an operating position in which the front ends of said fingers are in engagement with the bottom of the last, each of said fingers having a crosspiece on its rear end and thus being substantially T-shaped, said means comprising a plurality of levers arranged in pairs, means mounting the two levers of each pair spaced from each other and each having a substantially circular aperture in its front end, said crosspiece having rounded ends rotatably mounted within said circular apertures of said two levers, and means above and spaced from each other for pivotally mounting said two levers for each finger at their rear ends.

7. In a lasting machine, a shank lasting mechanism comprising a plurality of individual wiper fingers of an equal length at least at one side of a central vertical longitudinal plane of a last and disposed closely adjacent to and slideable relative to each other, and means for moving each of said fingers within a vertical plane into one of a plurality of positions which are parallel to each other and independently of the other fingers from a basic position spaced from the bottom of the last to an operating position in which the front ends of said fingers are in engagement with the bottom of the last, said means comprising a plurality of upper and lower levers arranged in pairs, means mounting the two levers of each pair spaced from each other and the corresponding levers of each pair closely adjacent to and slideable relative to each other, means for pivotably connecting the rear ends of each of said fingers to the front ends of said two levers, and an upper shaft and a lower shaft spaced from each other pivotably supporting the rear ends of all of said upper and lower levers, respectively, both of said shafts being curved substantially in accordance with the contour of the shank of the last at said side of said vertical plane thereof.

8. In a lasting machine, a shank lasting mechanism

comprising a plurality of individual wiper fingers of an equal length at least at one side of a central vertical longitudinal plane of a last and disposed closely adjacent to and slidable relative to each other, means for moving each of said fingers within a vertical plane into one of a plurality of positions which are parallel to each other and independently of the other fingers from a basic position spaced from the bottom of the last to an operating position in which the front ends of said fingers are in engagement with the bottom of the last, said means comprising a plurality of upper and lower levers arranged in pairs, means mounting the two levers of each pair spaced from each other and the corresponding levers of each pair closely adjacent to and slidable relative to each other, means for pivotably connecting the rear ends of each of said fingers to the front ends of said two levers, and an upper shaft and a lower shaft spaced from each other pivotably supporting the rear ends of all of said upper and lower levers, respectively, both of said shafts being curved substantially in accordance with the contour of the shank of the last at said side of said vertical plane thereof, and means for shifting all of said levers simultaneously along said shafts for adjusting said fingers in the longitudinal direction of the shank of the last.

9. In a lasting machine, a shank lasting mechanism comprising a plurality of individual wiper fingers at least at one side of a central vertical longitudinal plane of a last and disposed closely adjacent to and slidable relative to each other, means for moving each of said fingers within a vertical plane into one of a plurality of positions which are parallel to each other and independently of the other fingers from a basic position spaced from the bottom of the last to an operating position in which the front ends of said fingers are in engagement with the bottom of the last, said means comprising a plurality of upper and lower levers arranged in pairs, means mounting the two levers of each pair spaced from each other and the corresponding levers of each pair closely adjacent to and slidable relative to each other, means for pivotably connecting the rear ends of each of said fingers to the front ends of said two levers, and a straight upper shaft and a straight lower shaft parallel to and spaced from each other at a distance substantially equal to the distance between said connecting means on the front ends of said two levers and pivotably supporting the rear ends of all of said upper and lower levers, respectively, said fingers having different lengths so that a line connecting the front ends of the adjacent fingers is curved substantially in accordance with the contour of the shank of the last at said side of said vertical plane thereof.

10. In a lasting machine having at least one tong-shaped end wiper with a pair of plates pivotably connected to each other at a point spaced from a last in the longitudinal direction thereof and pivotable relative to at least one end part of the last for lasting the corresponding end part of an upper to an insole, a plurality of shank wiper fingers on each side of a central vertical longitudinal plane of the last, means for moving said fingers within a vertical plane from a basic position spaced from the bottom of the last to an operative position in engagement with the bottom of the last, and a plurality of auxiliary wiper fingers on each side of said vertical plane for lasting the part of the upper intermediate said end part and said shank thereof, spring means acting upon each of said auxiliary fingers and tending to move the same individually from a position spaced from said last toward an operative position in engagement with the last, and stop means on said end wiper for determining the number of auxiliary fingers capable of being moved by said spring means toward said last and underneath the lasting margin of the upper.

11. In a lasting machine having at least one tong-shaped end wiper with a pair of plates pivotably connected to

each other at a point spaced from a last in the longitudinal direction thereof and pivotable relative to at least one end part of the last for lasting the corresponding end part of an upper to an insole, a plurality of shank wiper fingers on each side of a central vertical longitudinal plane of the last, means for moving said fingers within a vertical plane from a basic position spaced from the bottom of the last to an operative position in engagement with the bottom of the last, and a plurality of auxiliary wiper fingers on each side of said vertical plane for lasting the part of the upper intermediate said end part and said shank thereof, spring means acting upon each of said auxiliary fingers and tending to move the same individually from a position spaced from said last toward an operative position in engagement with the last, each of said plates of said end wiper having a recess in the outer side thereof at the free end directed toward the shank of the last and forming a stop edge for limiting the number of auxiliary fingers capable of being moved by said spring means toward said last and underneath the lasting margin of the upper.

12. In a lasting machine having at least one tong-shaped end wiper with a pair of plates pivotably connected to each other at a point spaced from a last in the longitudinal direction thereof and pivotable relative to at least one end part of the last for lasting the corresponding end part of an upper to an insole, a plurality of shank wiper fingers on each side of a central vertical longitudinal plane of the last, a housing partly enclosing and guiding said shank wiper fingers, means for moving said fingers within a vertical plane from a basic position spaced from the bottom of the last to an operative position in engagement with the bottom of the last, a plurality of auxiliary wiper fingers on each side of said vertical plane for lasting the part of the upper intermediate said end part and said shank thereof, spring means acting upon each of said auxiliary fingers and tending to move the same individually from a position spaced from said last toward an operative position in engagement with the last, stop means on said end wiper for determining the number of auxiliary fingers capable of being moved by said spring means toward said last and underneath the lasting margin of the upper, each of said auxiliary fingers having an elongated slot extending in the direction of movement of said finger, and a pin connected to said housing of said shank wiper fingers and extending through said slots of said auxiliary fingers for limiting the extent of the movement of the auxiliary fingers toward said last which do not engage with said stop means.

13. In a lasting machine having at least one tong-shaped end wiper with a pair of plates pivotably connected to each other at a point spaced from a last in the longitudinal direction thereof and pivotable relative to at least one end part of the last for lasting the corresponding end part of an upper to an insole, a plurality of shank finger wipers on each side of a central vertical longitudinal plane of the last and disposed closely adjacent to and slidable relative to each other, means for moving each of said fingers within a substantially vertical plane and parallel to and independently of the other fingers from a basic position spaced from the bottom of the last to an operating position in which the front ends of said fingers are in engagement with the bottom of the last, said means comprising a plurality of upper and lower levers arranged in pairs, means mounting the two levers of each pair spaced from each other and the corresponding levers of each pair closely adjacent to and slidable relative to each other, means for pivotably connecting the rear ends of each of said fingers to the front ends of each of said two levers, a housing laterally enclosing all of said levers and the rear ends of said fingers at each side of said vertical plane of the last, and an upper shaft and a lower shaft mounted in said housing parallel to and spaced from each other at a distance substantially equal to the dis-

tance between said connecting means on the front ends of said two levers and pivotally supporting the rear ends of all of said upper and lower levers, respectively, the front ends of said fingers having different lengths so that a line connecting said front ends of the adjacent fingers at each side of said vertical plane of the last is curved substantially in accordance with the contour of the shank at said side of said last, spring means acting upon each pair of said levers for moving said fingers to the bottom of the shank, a plurality of auxiliary wiper fingers on each side of said vertical plane for lasting the part of the upper intermediate said end part and said shank thereof, spring means acting upon each of said auxiliary fingers and tending to move the same individually toward the last, stop means on said end wiper for determining the number of auxiliary fingers capable of being moved by said last spring means toward said last and underneath the lasting margin of the upper, and means for moving said housing containing said levers and the rear ends of said shank wiper fingers and also said auxiliary fingers in a direction transverse to the direction of movement of said individual shank wiper fingers.

14. In a lasting machine having at least one tong-shaped end wiper with a pair of plates pivotably connected to each other at a point spaced from a last in the longitudinal direction thereof and pivotable relative to at least one end part of the last for lasting the corresponding end part of an upper to an insole, a plurality of shank wiper fingers on each side of a central vertical longitudinal plane of the last, means for moving said fingers within a vertical plane from a basic position spaced from the bottom of the last to an operative position in engagement with the bottom of the last, a plurality of auxiliary wiper fingers on each side of said vertical plane for lasting the part of the upper intermediate said end part and said shank thereof, spring means acting upon each of said auxiliary fingers and tending to move the same individually from a position spaced from said last toward an operative position in engagement with the last, stop means on said end wiper for determining the number of auxiliary fingers capable of being moved by said spring means toward said last and underneath the lasting margin of the upper and stop means for locking said auxiliary fingers in said operative position.

15. In a lasting machine having at least one long-shaped end wiper with a pair of plates pivotably connected to each other at a point spaced from a last in the longitudinal direction thereof and pivotable relative to at least one end part of the last for lasting the corresponding end part of an upper to an insole, each of said plates having an extension directed toward the shank portion of a last and of such a length that the folds on the lasting margin of the upper formed behind the area of operation of the end wiper by the lasting of the respective end of said margin will be folded against the insole in the direction toward the shank by the side of the extensions facing the insole, a plurality of shank wiper fingers on each side of a central vertical longitudinal plane of the last, means for moving said fingers within a vertical plane from a basic position spaced from the bottom of the last to an operative position in engagement with the bottom of the last, and a plurality of auxiliary wiper fingers on each side of said vertical plane for lasting the part of the upper intermediate said end part and said shank thereof, spring means acting upon each of said auxiliary fingers and tending to move the same individually from a position spaced from said last toward an operative position in engagement with the last, each of said plates of said end wiper having a recess in the outer side thereof at the free end directed toward the shank of the last and forming a stop edge for limiting the number of auxiliary fingers capable of being moved by said spring means toward said last and underneath the lasting margin of the upper.

16. In a lasting machine having at least one tong-shaped

end wiper with a pair of plates pivotably connected to each other at a point spaced from a last in the longitudinal direction thereof and pivotable relative to at least one end part of the last for lasting the corresponding end part of an upper to an insole, each of said plates having an extension directed toward the shank portion and of such a length that the folds on the lasting margin of the upper formed behind the area of operation of the end wiper by the lasting of the respective end of said margin will be folded against the insole in the direction toward the shank by the side of the extensions facing the insole, a plurality of shank wiper fingers on each side of a central vertical longitudinal plane of the last, means for moving said fingers within a vertical plane from a basic position spaced from the bottom of the last to an operative position in engagement with the bottom of the last, and a plurality of auxiliary wiper fingers on each side of said vertical plane for lasting the part of the upper intermediate said end part and said shank thereof, spring means acting upon each of said auxiliary fingers and tending to move the same individually from a position spaced from said last toward an operative position in engagement with the last, each of said plates of said end wiper having a recess in the outer side thereof at the free end directed toward the shank of the last and forming a stop edge for limiting the number of auxiliary fingers capable of being moved by said spring means toward said last and underneath the lasting margin of the upper and across said extensions for pressing said folds on the lasting margin of the upper against the insole.

17. In a lasting machine having at least one tong-shaped end wiper with a pair of plates pivotably connected to each other at a point spaced from a last in the longitudinal direction thereof and pivotable relative to at least one end part of the last for lasting the corresponding end part of the upper to an insole, each of said plates having an extension directed toward the shank portion and of a length adapted to fold over against the insole the folds on the lasting margin of the upper formed by the lasting of the respective end of said margin behind the area of operation of the end wiper, said extensions being offset from the surface of the plates adapted to face the insole so as to increase the size of the gap for receiving the auxiliary fingers between the insole and the extensions, a plurality of shank wiper fingers on each side of a central vertical longitudinal plane of the last, means for moving said fingers within a vertical plane from a basic position spaced from the bottom of the last to an operative position in engagement with the bottom of the last, and a plurality of auxiliary wiper fingers on each side of said vertical plane for lasting the part of the upper intermediate said end part and said shank thereof, spring means acting upon each of said auxiliary fingers and tending to move the same individually from a position spaced from said last toward an operative position in engagement with the last, each of said plates of said end wiper having a recess in the outer side thereof at the free end directed toward the shank of the last and forming a stop edge for limiting the number of auxiliary fingers capable of being moved by said spring means toward said last and underneath the lasting margin of the upper.

18. In a lasting machine, a shank lasting mechanism comprising a plurality of individual wiper fingers at least at one side of a central vertical longitudinal plane of a last, and means including a biasing assembly for moving each of said fingers within a vertical plane into one of a plurality of positions which are parallel to each other and independently of the other fingers from a basic position spaced from the bottom of the last to an operating position in engagement with the bottom of the last.

19. A mechanism as defined in claim 18 wherein said means moves all of said fingers simultaneously.

20. A mechanism as defined in claim 18 wherein said moving means simultaneously returns said fingers to their basic position.

21. A shank lasting machine for use with a last having a vertical longitudinal plane comprising finger-like wipers; means mounting said wipers for vertical movement into positions which are parallel to each other to adjust to the shape of the shank of the last; and force applying means for automatically moving the wipers independently of one another from a basic position in which they are disposed at a vertical distance from the bottom of the last into an operating position in which they touch the bottom of the last. 5
